Primary Examiner — Calvin E Vansant*Assistant Examiner* — Sherry L Jones(57) **CLAIM**

The ornamental design for a cat litter box as shown and described.

DESCRIPTION

FIG. 1 is a front elevational view of a cat litter box showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof; and,

FIG. 7 is a perspective view thereof.

The logo “FaFaBa Pet” forming part of the claimed design is a registered trademark of NINGBO DINGWEI PET CO., LTD.

The broken lines in the drawings depict portions of the cat litter box that form no part of the claimed design.

1 Claim, 7 Drawing Sheets(56)
